DISCHARGE LAMP

Earl C. Brueckmann, Bloomfield, N. J., assignor,
by mesne assignments, to Westinghouse Electric and Manufacturing Company, East Pittsburgh, Pa., a corporation of Pennsylvania

Application January 10, 1935, Serial No. 1,142

9 Claims. (Cl. 176—122)

This invention relates to discharge devices and more particularly to devices in which a metallic vapor is employed as the ionizable medium.

In certain devices of the above character and particularly in devices using sodium, cadmium, mercury or other vapor condensable at room temperature, it is necessary to provide a relatively high voltage to start the device. Although it is the practice to include a rare gas such as argon or neon to promote starting in the above devices, a relatively high starting voltage is required, whereas when the metal sodium, for example, is vaporized, the device operates at relatively low voltage. It is necessary, however, in order to gain the benefit of low voltage for starting, to heat the vaporizable material. Furthermore, when lamps of the above character are operated under low temperature conditions, as when used out of doors in cold climates, great difficulty is encountered in starting.

Lamps as heretofore constructed start at 150 volts at a temperature of 25 degrees centigrade, at 200 volts at a temperature of zero degrees centigrade and at 300 volts at a temperature of ten below zero centigrade. This makes them impractical for outdoor winter service.

It is, therefore, an object of the present invention to provide a lamp of the character described which will start at relatively low voltage at relatively low temperature.

Another object of the invention is to provide a lamp in which a heat source is furnished to facilitate starting.

A further object of the invention is to provide a lamp wherein a source of heat is provided to facilitate starting and in which the heat supply is terminated when the lamp reaches an operating temperature.

Other objects and advantages of the invention will be more clearly understood by reference to the following description, together with the accompanying drawing, in which—

Fig. 1 is a side elevational view of a device constructed in accordance with the present invention;

Fig. 2 is a view taken on line II—II in Fig. 1; and

Fig. 3 is a view taken on line III—III in Fig. 1.

A device constructed in accordance with the present invention may comprise a tubular sealed envelope 10 having electrodes 11 and 12 mounted on conductive support members 13 and 14 respectively and sealed through opposite ends walls of the envelope. The electrodes may be of any suitable construction in which a metallic body is pro-

vided with an electron emission material. An electrode of this character is shown and described in copending application Serial No. 733,168 filed June 30, 1934 and assigned to the present assignee.

The bulb 10 may be mounted in an outer sealed envelope or jacket 15 having a press 16 at one end. The jacket 15 provides an outer heat insulating chamber for the discharge envelope 10. The conductor 14 of the electrode 12 is sealed through the press 16 and connects with a lead wire or conductor 17. The conductor 13 of the electrode 11 is connected, as by means of a wire 17', with a conductive supporting member 18 which member is sealed through the press 16 and connected to a conductor or lead wire 19. The supporting conductor 18 is provided with arms 21 which embrace and support the envelope 10.

A heater element or filament 22 is disposed at one end, preferably at the lower end, of the jacket or chamber 15. This filament may be of tungsten wire helically wound and in the form of a ring having one terminal 23 connected with the conductive support 18 and the other terminal 24 connected with a conductor 25. Support wires 26 extending from a button of glass, or other insulative material, may be employed to support the filament and the button may be mounted on an end of the lead wire 13 extending from the chamber 10.

The conductor 25 may be supported by means of a connector piece 27 which is secured in the press 16. The conductor 25 may be insulated throughout substantially its length and provided with an exposed contact portion 28 for engagement with an end of a heat responsive element in the form of a bimetallic member 29. The other end of the member 29 may be connected by means of a conductor 31 to the conductor 14 and consequently with the lead wire 17. For the purpose of supporting conductor 25 in fixed relation to the bulb, a pair of resilient members 32 and 33 are provided.

Each of these members may include a strip 34 in the form of a ring of less diameter than the inside diameter of the outer jacket and tension members 35 may be provided to hold the rings in resilient spaced relation with respect to the surface of the outer jacket. Connector members 36 and 37 may be provided for securing the conductor 25 and the supporting conductor 18 respectively to hold them in fixed relation.

When the device is cold, the bimetallic member 29 makes contact with the conductor 25 and as electrical energy flows through the lead wires 55

17 and 19, current flows through the filament 22, conductor 18 and lead wire 19. Owing to the initial resistance within the bulb 10 before ionization occurs, substantially all the current will flow 5 through the filament heating it to relatively high temperature. A voltage drop, however, occurs between the electrodes and they become emissive, ionizing the gas and a discharge occurs so that current flows through conductor 14, through the 10 ionized gas, conductor 13 and through conductor 18 to lead wire 19. As the device heats up the thermostat which is in close proximity to the wall of the chamber 10 is affected and the bimetallic member moves to break the circuit cutting out 15 the filament, thus permitting the full current flow between the electrodes.

If for any reason the current is terminated and no discharge occurs, the device will cool down and the vapor will condense. At a predetermined temperature the bimetallic member will again cause current to flow through the filament when the current flow is reestablished. Thus the temperature of the device will be elevated with the result that the metallic vapor such as, for example, mercury vapor will again be vaporized for 20 ionization and a discharge will occur between the electrodes.

When a lamp as above described is put into operation the heater element will radiate sufficient heat to vaporize the ionizable medium so that when sufficient voltage is impressed between the electrodes they will become heated and electron emissive causing a discharge current to flow and the device to operate. The heat from 30 the discharge then causes the heat responsive element to break the heater circuit. If the lamp becomes inoperative by reason of a temporary interruption of current, the heat-responsive element will still keep the heater circuit open as 35 long as the lamp is hot enough to act upon the said element. Thus the heat from the heater element will not elevate the temperature of the device to such a degree as to prevent restarting.

Although it is desirable to provide a cut-out 45 means for terminating the flow of current through the filament it may be desirable to have the filament heated during the operation of the lamp especially when the lamp is operated out of doors in very cold weather. In such case the 50 filament will receive part of the full current flow and emanate a given amount of heat energy.

A high intensity mercury lamp of the present character may be operated at 150 volts across the lamp on a line voltage of from 208 to 240 55 volts, a reactance being used in series with the lamp. The lamp may, however, start at a considerably higher voltage than the voltage at which it operates. As the temperature drops below or rises above normal room temperature there is a 60 considerable increase in the starting voltage. Thus, if the temperature of the lamp is low, resulting in an increase in the starting voltage the heater element as provided in accordance with the present invention decreases the starting voltage 65 from say 300 volts to 200 volts by raising the temperature of the lamp from zero degrees centigrade to 20 degrees centigrade.

Although a preferred embodiment of the invention is shown and described herein it is to be 70 understood that modifications may be made therein without departing from the spirit and scope of the invention as set forth in the appended claims.

What is claimed:

75 1. A discharge device comprising a sealed en-

velope, containing a metallic vapor, electrodes in said envelope, a heater element, a heater circuit including said heater element, a heat responsive element for making and breaking said circuit disposed intermediate the ends of said envelope, a discharge circuit including said electrodes when said vapor is ionized to carry a discharge current, said heat responsive element operating to break said heater circuit when said discharge elevates the temperature of said element to a predetermined degree, said element operating upon a decrease in temperature to close said circuit for a flow of current through said heater. 5 10

2. A discharge device comprising a sealed envelope, containing a metallic vapor, electrodes in said envelope, a heater element, a heater circuit including said heater element, a heat responsive element for making and breaking said circuit, a discharge circuit including said electrodes when said vapor is ionized to carry a discharge current, said heat responsive element positioned between said electrodes and adjacent to the path of discharge and operating to break said heater circuit when said discharge elevates the temperature of 25 said element to a predetermined degree. 15

3. A discharge device comprising sealed outer and inner envelopes, an ionizable medium in said inner envelope, a pair of electrodes in said inner envelope, a heater element in said outer envelope 30 positioned to radiate heat energy to said inner envelope, means for causing a flow of electrical energy through said envelopes, means for producing a discharge between said electrodes, and an element within said outer envelope responsive 35 to heat radiated from said discharge for making and breaking the circuit through said heater element, and disposed intermediate said electrodes, to terminate the flow of electrical energy in said heater element when the heat of the discharge 40 raises said heat-responsive element to a predetermined temperature. 40

4. A discharge device comprising sealed outer and inner envelopes, an ionizable medium in said inner envelope, a pair of electrodes in said inner envelope, a heater element in said outer envelope 45 positioned to radiate heat energy to said inner envelope, means for causing a flow of electrical energy through said envelopes, means for producing a discharge between said electrodes, and 50 an element within said outer envelope disposed in close relation to the discharge path and intermediate the ends thereof, either responsive to heat radiated from said discharge to terminate the flow of electrical energy in said heater 55 element, or operating to cause a flow of electrical energy through said heater element. 55

5. A discharge device comprising an inner and an outer chamber, an ionizable medium and electrodes disposed at opposite ends of said inner chamber, a heater element in said outer chamber, an electrical circuit for said heater, a bi-metallic element in said circuit and positioned within said outer chamber and intermediate said electrodes to be heated when a discharge occurs between 60 said electrodes, said element operating when heated to terminate the flow of electrical energy 65 through said heater element. 65

6. A discharge device comprising an inner and an outer chamber, an ionizable medium and electrodes at opposite ends of said inner chamber, a heater element in said outer chamber, an electrical circuit for said heater, a bi-metallic element in said circuit and positioned within said outer chamber and intermediate said electrodes 70 75

to be heated when a discharge occurs between said electrodes, said element operating when heated to terminate the flow of electrical energy through said heater element, and operable to cause a flow 5 of electrical energy through said heater in the absence of heat upon a termination of said discharge.

7. A discharge device comprising a generally cylindrical inner envelope containing an ionizable medium and an electrode disposed therein adjacent each end, an enclosing generally cylindrical envelope, means for supporting said inner envelope in said enclosing envelope and including conductors electrically connected to said electrodes, and a heater element in the space between said envelopes, said heater element being connected across said conductors in series with a bimetallic cut-out element traversing a substantial part of the length of said inner envelope, whereby 10 when the device is operated current first passes through said heater and bimetallic elements until the temperature of the inner envelope is raised sufficiently to cause a discharge between said electrodes, with the eventual opening of the circuit 15 through said heater element by the thermal actuation of said bimetallic element.

8. A discharge device comprising a sealed envelope containing an ionizable medium, electrodes, a heater element and circuit including said element, a heat-responsive device for making and

breaking said circuit, a discharge circuit including said electrodes when said medium is ionized to carry a discharge current, said heat-responsive device being positioned between said electrodes and adjacent the path of said discharge 5 current, and operating to break said heater circuit when said current elevates the temperature of said device to a predetermined degree, and causing current to again flow through said heater element upon a decrease in the temperature of said 10 device to one below that breaking said circuit.

9. A discharge device comprising sealed outer and inner envelopes, an ionizable medium and a pair of electrodes in said inner envelope, a heater element in said outer envelope positioned to 15 radiate heat energy to said inner envelope, means for causing a flow of electrical energy through said inner envelope and producing a discharge between said electrodes and a circuit in parallel therewith for energizing said heater element, and an element disposed intermediate said electrodes, within said outer envelope, and responsive to heat radiated from said discharge, for making and breaking said circuit through said heater element, in order to terminate the energization of said 20 heater element when the discharge raises said heat-responsive element to a predetermined temperature.
